UNITED STATES PATENT OFFICE.

CHARLES P. MADSEN, OF CHICAGO, ILLINOIS, ASSIGNOR, BY MESNE ASSIGNMENTS,
TO PELOUZE MANUFACTURING COMPANY, OF CHICAGO, ILLINOIS, A CORPORATION
OF ILLINOIS.

ELECTRIC HEATING DEVICE.

1,034,265.

Specification of Letters Patent. Patented July 30, 1912.

Original application filed January 22, 1908, Serial No. 412,176. Divided and this application filed February 11, 1911. Serial No. 608,003.

To all whom it may concern:

Be it known that I, CHARLES P. MADSEN, a citizen of the United States, and resident of Chicago, Cook county, Illinois, have invented certain new and useful Improvements in an Electric Heating Device, of which the following is a full, true, clear, and exact description, such as will enable others skilled in the art to which it appertains to make and use the same.

My invention relates to electrical heating devices and more particularly to electrical heaters for sad irons and the like.

The object of my invention is to provide an electric heater wherein the heating portion or element will be arranged in a single plane and capable of being placed in close proximity to the article to be heated, thereby preventing loss of heat by dissipation; which will have a suitable mounting for the heating element wherein the conductor is embedded and suitably insulated; and which may be made as a separate and distinct article of manufacture at comparatively low cost and capable of being mounted or removed as a unitary self-contained structure in the body of a sad iron or like article to be heated.

Another and more particular object of my invention is to provide a sad iron which will have a member to be heated and a member for supplying the necessary heat thereto, which member will be a self-contained structure associated with the heated member but readily separable therefrom as a unit.

Broadly my invention consists in an electrical heating device comprising a mounting or supporting part and an electrical heating member comprising a pre-formed heating coil, the turns of which are separated by insulating material preferably wound up simultaneously with the conductor in a single plane, and preferably bound together by a layer of insulating cement, the whole wound form being bodily cemented to said mounting.

My invention further consists of a heating element, as above stated, which may be made in the form of a unit adapted for mounting in the body of the sad iron and for interlocking coöperation with the other

parts of the iron, the body of the iron being so constructed that the several elements thereof can be readily disassembled or assembled by a person unskilled in such matters, and the heating element removed or replaced without disturbing the proper and pre-arranged relations of all of the parts of the iron.

I will describe my invention by reference to the accompanying drawings wherein:

Figure 1 is a side elevation of a sad iron embodying my invention; Fig. 2 is a transverse vertical section on line 2—2 of Fig. 1; Fig. 3 is a vertical, longitudinal sectional view taken through the center of the iron shown in Fig. 1; Fig. 4 is a view similar to Fig. 2, but taken on the line 4—4 of Fig. 3; Fig. 5 is a perspective view of the heating member; Figs. 6 and 7 are perspective views of the mounting and the pre-formed heating element respectively ready to be assembled; Fig. 8 is an enlarged transverse sectional view of a portion of the heater showing the detailed construction thereof; and Fig. 9 is a bottom plan view of a modified form of heater.

As will hereinafter appear, my invention is capable of being adapted by suitable modification to various articles to be heated, but for the purposes of illustration I have chosen one embodiment of my invention which has been particularly designed for heating sad irons of the type described and claimed in my co-pending application, Serial No. 412,176, filed January 22nd, 1908, wherein my present invention was originally fully disclosed.

In general the body portion of the iron comprises a top or weight element W and a bottom element or ironing plate H, and between and separating these parts is interposed the heater member I. By this arrangement the heater serves to insulate the member W from the bottom plate H so as to prevent the heat from reaching said member W and rendering it too hot for comfortable use. A suitable handle G is provided for manipulating the iron and is carried by an upstanding post or standard P secured to the front end of the iron.

The heater (Figs. 5 to 9 inclusive) con-

sists of a backing plate or mounting 1 and a heating conductor 2 buried or embedded in one side thereof. The mounting 1 may be of any suitable material, but I prefer to 5 make it of insulating material which is preferably tough, refractory and substantially incompressible material suitably conformed to the desired shape by hydraulic pressure. These qualities render it capable 10 of withstanding the blows to which it is subjected when used in a sad iron heater and furthermore it properly insulates the two other portions of the iron between which the heater is interposed. Obviously it may 15 be given any suitable shape to adapt it to the article which is to be heated, but in the present structure I have shown it as substantially triangular in shape and conforming to the general shape of the sad iron.

20 The heating conductor 2 is preferably a resistance ribbon of suitable cross-sectional area to give the desired results, but it is obvious that a resistance wire of circular or other geometric cross-section may be used if 25 desired. This conductor is arranged in the form of a thin, flat coil before it is applied to its mounting. In making this heater coil I wind the heating conductor volutely in one plane although I may, if desired, wind it 30 reflexively in a single plane, the ribbon being presented edgewise to the mounting plate. I prefer to insulate the turns of the coil by a comparatively soft, loose material, such as asbestos. This I prefer as an insulating 35 substance for the reason that it effectively withstands the heat and it permits the resistance ribbon to expand or contract with the variations in temperature. It is possible to interpose loose asbestos between the 40 turns after the coil is wound, but because of the impracticability of this method I use a ribbon or strip 2' of asbestos about as wide as the resistance ribbon and somewhat thicker and to wind it up in parallel with 45 the resistance ribbon. I prefer, however, to use an asbestos string, thread or yarn which can be bought standard on the market and which assumes the form of a ribbon due to the pressure in winding.

50 The process of making the heater form may be accomplished by winding the ribbon and asbestos strip together in a single plane between two plates. Incidentally the coil 55 may be given a substantially triangular shape, or any other suitable geometric figure, during this process of winding to adapt it to the particular article to be heated. The turns of both the ribbon and the asbestos are closely compacted upon each other during 60 the process of winding so that when the wound form is removed from the winding machine it will be found to be in a more or less self-sustaining condition and in this condition it may be applied to the backing plate 65 without further preparation. However, in

ordinary factory methods of manufacture the form would naturally be subjected to some handling before it is mounted on the backing member. For this reason I prefer to bind the turns together more substantially. I may, if desired, trail the asbestos through a bath of liquid cement or adhesive prior to winding it in the coil, but I find that the best method with a ribbon conductor is to apply a binding layer of insulating 70 cement 3 on one face or side of the form, this being generally done as soon as the coil is removed from the winding machine. By applying a thin layer of cement in this manner the turns of the winding are firmly 75 secured and the whole wound form rendered comparatively stiff and unitary so that it will withstand considerable handling before it is firmly mounted. Especial care need not be taken, as shown in Fig. 7, to apply this 80 first layer of cement with any degree of uniformity for the reason that it serves principally as a binder unless a metal backing plate is used. In this case the cement had better be applied smoothly and evenly 85 so as to properly insulate the conductor from the plate. The cement which I find to be the most satisfactory for this purpose, is of the self-hardening kind, that is, cement which is made of a pasty consistency and 90 which solidifies or hardens on drying.

While it is possible to provide the insulating plate 1 with a smooth, flat surface and attach the formed heater coil by additional cement, I find by experiment that a more 100 satisfactory structure is obtained by making a broad, shallow, flat-bottomed recess 1' in one side of the plate and placing the heater form flat against the bottom of this recess, and burying or embedding the form 105 therein by means of more cement as indicated by 3'. This additional quantity of cement fills in around the edges of the heater form and also fills other interstices so that the face of the heater element presents a 110 generally smooth appearance.

Fig. 7 shows a pre-formed heater coil with the binder layer of cement roughly applied, portions of the winding being exposed to the atmosphere. This form is ready to be embedded in the plate 1 with its cemented side against the bottom of the recess 1'.

My purpose in winding the ribbon in triangular form with an open center 3'' is to distribute the heat more around the edges 120 and point of the iron since the points come in contact with the damp cloth first, the center of the ironing surface being left comparatively cooler so as not to scorch the cloth. Fig. 9 shows the heater coil wound in 125 a modified form so that the middle and rear portions of the iron are heated less than the remaining portions.

To complete the heater unit, the inner and outer ends of the ribbon are connected to up- 130

standing contact blades 6 which constitute terminals for the winding (Figs. 3, 4 and 5). The blades are held in parallel relation by means of an insulating block or column 7 which is fitted and secured into a rectangular opening 8 in the insulating plate I. The contact plates project upwardly beyond the upper end of the post 7 and into a channel or recess 9 in the upper side of the member 10 W so that they are in position to coöperate with a movable switch plug for connecting the heater to the source of current.

The ironing plate or bottom element of the iron comprises a flat, thin, rimless metal plate H, substantially triangular in shape, and having a polished bottom surface for ironing purposes. This plate has an upstanding enlargement H' centrally located and preferably of triangular shape so as to 15 interlock with the correspondingly shaped recess or socket I' in the heating member, the object of this arrangement being to prevent relative rotation of the heating member and the plate. The under face of the 20 heater unit, wherein is embedded the heating coil, lies flat against the upper face H' of the bottom plate so that the heat is transmitted directly to the plate without any loss. In order to provide against any possibility 25 of the exposed edges of the heating conductor 2 coming in contact with the metal of the ironing plate, I prefer to interpose a thin sheet of mica M.

As previously stated, the heater element 30 constitutes an intermediate member of the body of the iron and is interposed between the weight member W and the bottom member or plate H. It is particularly desirable that the upper portion of the body of the 35 iron and the handle be maintained as cool as possible and for that reason I have provided the member W with a large cavity 10 which fits over and is preferably completely filled by the upper portion of the heating member, as clearly shown in Figs. 2, 3 and 40 45. This provides a comparatively thick body of insulating material between the member W and the heating member so that practically no heat is dissipated into the upper portion of the iron. The bottom 50 edges of the member W (Figs. 3 and 4) are comparatively thin and fit the shouldered edge I''' of the heater so as to provide a peripheral interlock between said parts. It 55 will thus be seen that when the ironing plate, the heater member and the weight member are assembled together they are all interlocked with each other and there is no 60 possibility of displacement or relative rotation. In order to clamp these parts in their proper relation, I provide the ironing plate with a central upstanding bolt or post 12 which passes upwardly through holes in the heating member and the weight member W, 65 and upon its upper end threaded to receive

the wing clamping nut 13. The hole 14 in the member W through which the bolt passes is enlarged to prevent mechanical contact and eliminate the possibility of the member W absorbing heat from the post. 70 The insulation of the upper member is further perfected by means of an insulating washer 15 clamped under the nut 13. The wing nut, washer and the upper end of the bolt all lie within a deep depression or recess 16 in the upper member. 75

As before stated, the contact blades 6 of the heater element project upwardly beyond the upper end of the insulating post 7 and into the rectangular groove or recess 9. 80 This channel or recess 9 extends to the rear end of the iron and constitutes a guide for the movable switch plug R. This switch plug is preferably reciprocatory or movable in the guide channel so that it may be moved 85 to engage or disengage the contact blades. I have positioned this switch on the iron beneath the handle G in such manner that it may be moved by the hand gripping the handle when the iron is in use. By means of 90 this arrangement the temperature may be regulated by switching on or off of the current without interrupting the process of ironing. In addition to this I have arranged 95 this plug so that it may be entirely removed from the iron when it is desired to completely disconnect the same from the circuit. The small knob 18 carried by the switch forms a convenient means by which the 100 switch is operated. The switch is yieldingly maintained in its guide channel by means of a spring member 19, one end of which is clamped under the insulating washer 15 which holds it securely in place. The other 105 end of the spring lies above the switch plug and substantially parallel thereto. This end of the spring is bifurcated and the free ends of the bifurcations are bent to form latches which snap into the grooves 20 in the upper 110 face of the switch block. These grooves correspond to the different positions of the switch in its channel; thus this spring yieldingly presses upon the switch and holds it in either of its positions, but does not interfere with the complete removal of the switch 115 block from the iron to completely disconnect the same. The switch plug itself may be of any suitable construction, but I find the form shown particularly in Figs. 3 and 4 to be best adapted to the sad iron shown in 120 the drawings. The switch comprises a small rectangular block having two parallel longitudinal bores 21 and slots 22 communicating therewith. The slots and bores provide openings or recesses to permit the contact blades 6 of the heater element to enter the switch block and engage the terminals 23 which are positioned in respective longitudinal bores of the plug. The conductors which 125 convey the current to the iron are secured to 130

these terminals and pass upward through holes in the block and make a double turn underneath an upstanding projection or bridge 24 which is adapted to take up the 5 strain on the conductor.

My invention is capable of embodiment in various modifications without departing from the spirit thereof. I desire therefore that my invention be construed accordingly.

10 The circuit closing and breaking device or mechanism described herein was originally disclosed in my copending application, Serial No. 412,176, filed January 22, 1908. Said mechanism forms the subject matter of 15 and is claimed in my copending application Serial No. 608,051 and is not specifically claimed herein. The said application 608,051 and this present application are both divisional applications of my copending application Serial No. 412,176.

I claim:

1. An electrical heating device comprising a body of insulating material having a rim upstanding from one face to form a 25 shallow depression for receiving a heating member, in combination with a heating member substantially as thick as the height of said rim and comprising a flatly wound ribbon conductor, a binder layer of insulating cement applied upon one face of said heating member, said member being adapted to be laid in said depression with its cemented face against the bottom of said depression and its outer face in the plane of 35 the outer edge of the rim, a quantity of insulating cement filling the spaces between said rim and said heating member and firmly securing said heating member in said depression, and a thin flat sheet of insulating 40 material laid flat upon and in contact with both the outer edges of the rim and the free surface of the heating member.

2. An electrical heating device comprising a body of insulating material having an 45 outer and an inner rim of even height upstanding from one face to form a shallow depression or trough for receiving a heating member, in combination with a flat heating member substantially as thick as the 50 height of said rims and comprising a suitably insulated, flatly wound conductor, a layer of insulating cement applied upon one face of said heating member, said member being laid bodily in said groove with its cemented face against the bottom thereon, a 55 quantity of insulating cement filling the spaces between said rims and said heating member and firmly securing said heating member in said depression, and an upstanding terminal on the opposite side of said mounting connected to said heating member.

60 3. In an electric heater for sad irons a mounting of insulating material conformed 65 to the shape of the iron, and having a broad,

shallow recess in one side also conformed to the shape of the iron, a pre-formed heating element conformed to the shape of the recess and comprising a ribbon resistance and a strip of insulating material compactly wound together in one plane, and permanently consolidated by a layer of cement applied to one face thereof, said heating element being laid in said depression, and a quantity of adhesive insulating material filling the remaining portions of said recess and spread over the other face of said coil for embedding said coil in said recess and presenting a smooth surface for contact with the article to be heated.

4. In an electric heater for sad irons, a comparatively thin, flat plate of hard refractory insulating material of substantially triangular shape and having a central opening, an inner and an outer upstanding rim forming therebetween a broad, shallow recess of substantially uniform depth throughout for receiving a heating element, in combination with a pre-formed heating coil comprising a ribbon resistance and a strip of asbestos wound together in a single plane, insulating material securing the turns of said heating coil together, said coil being substantially as thick as the depth of said recess and conformed to fit therein, and a quantity of adhesive insulating material firmly securing said coil in place in said recess.

5. As an article of manufacture an electric heating element comprising a substantially triangular pre-formed, self-sustaining heating element arranged in a thin, flat plate, a correspondingly shaped flat plate of hard refractory insulating material having a recess in one face for receiving said pre-formed heating element, and a quantity of insulating cement holding said heating element securely within said recess and substantially flush with the edges thereof.

6. A heater unit adapted for mounting in 110 the body of a sad iron, comprising a flat, triangular plate of refractory insulating material having a central portion for interlockment with the portion of the iron to be heated, a comparatively broad recess in the 115 face of said plate, a pre-formed heating coil comprising a ribbon resistance and a strip of asbestos wound together in a thin, flat plane, a layer of cement binding the turns of said coil together, said coil being laid in 120 said recess in substantially mechanical contact with the portion of the iron to be heated, and a quantity of insulating cement embedding said coil and securing it firmly in 125 said recess.

7. An electric heater unit for sad irons, comprising a substantially triangular plate of hard refractory insulating material having a shouldered edge and having a broad, shallow depression in one side, in combina- 130

tion with an electric heater comprising a ribbon resistance and a strip of insulating material compactly wound volutely upon itself in a single plane, a layer of adhesive material binding the turns together, and a separate quantity of cement embedding and firmly attaching said heater in said recess.

In testimony whereof, I have hereunto set my hand, this 4th day of February, 1911, in the presence of two subscribing witnesses.

CHARLES P. MADSEN.
